[57] CLAIM

The ornamental design for a light transmitting panel, as
shown and described.

DESCRIPTION

FIG. 1 is a fragmentary plan view of a light transmitting
panel showing my new design the panel being fragmen-
tarily shown for convenience of illustration.

FIG. 2 is a plan view thereof on a greatly reduced scale.
FIG. 3 is an opposite plan view thereof on a greatly
reduced scale.

The panel has insubstantial thickness.
